BAG HOLDER

George K. Divelbiss, Clinton County, and
Albert Krofft, Easton, Mo.

Application November 22, 1943, Serial No. 511,294

1 Claim. (Cl. 248—99)

Our invention relates to improvements in bag holders, designed to support a bag with its mouth open while it is being filled.

The object of our invention is to provide a novel bag holder of the kind described, which is simple, cheap to make, strong, durable, easy to operate, easily and quickly assembled in operative condition, as easily and quickly disassembled into compact form for storage or shipment, and which is efficient in its operation.

The novel features of our invention are hereinafter fully described and claimed.

Our improved bag holder is illustrated, by way of example, in the accompanying drawing in which:

- Fig. 1 is a side elevation,
- Fig. 2 is a front elevation, and
- Fig. 3 is a top plan view.

Our improved bag holder is provided with a flat rectangular base 1 having through it a vertical hole, preferably other than circular in cross section, designated by 2, and shown as square in cross section. A vertical standard 3, square in cross section, is snugly fitted at its lower end in the hole 2, from which it may be readily removed, for disassembling, and which is firmly held by the base in its operative position.

A rectangular horizontal frame 4 has through it a vertical hole 5 through which the standard 3 extends and upon which standard, the frame is freely slideable upwardly and downwardly. Resilient means supports the frame 4 in its operative position, such means comprising a vertical coil spring 6 having at its upper end a hook 7 releasably engaging and supported by a pin 8 mounted in one side of the standard 3 adjacent to the upper end thereof and over the base 1. The lower end of the spring 6 has a hook 9 releasably engaging a screw eye 10 fastened in the upper side of the frame 4.

Two horizontal spreader bars 11 are mounted on the upper side of the frame 4 at opposite sides respectively of the standard 3, and are pivoted on vertical axes intermediate of their ends upon two vertical bolts 12 mounted in the frame 4 adjacent to the front edge thereof.

The spreader bars 11 are normally swung on the bolts 12 to the position shown in dotted lines in Fig. 3 by resilient means comprising, as shown, a horizontal coil spring 13, the ends of which are respectively attached to the rear ends of the spreader bars 11. The spreader bars 11 project forwardly from the front edge of the frame 4 and have mounted in them adjacent to their front ends two vertical bolts 14, which project respectively below the spreader bars 11. Two horizontal bag engaging members comprising, as

shown, two bars 15 are pivotally mounted on vertical axes on the lower ends of the bolts 14 respectively in the middle portions of said bag engaging members.

When the bag engaging members 15 are moved toward each other, to the proper positions, with the front end portions of the spreader bars 11, said bag engaging members are adapted to be inserted into and to support and spread open the mouth of a bag 16, when the bag is to be filled. By having the bag engaging members 15 pivoted at their middle portions on vertical axes to the spreader bars 11 respectively, the bag engaging members 15 may be easily and quickly swung to positions parallel with each other, into the open ends of different dimensioned bags, thus holding in open rectangular form, adapted for easy filling of the bags, the open ends thereof.

The tension of the spring 6 is such as to normally move the frame 4 to the uppermost position, shown in Fig. 1, in which position, the bag engaging members 15 will support the bag 16, when it is empty, with the bottom of the bag over and spaced from the base 1. After a predetermined amount of material, as shown in dotted lines, are indicated by 17 in Fig. 2, has been fed into the bag, the spring 6 will yield and lower the frame 4 to the position shown in Fig. 2, at which time the bottom of the bag will rest on the base 1 until the bag is filled. When this has been done, the bag is released from the members 15, and the spring 6 will retract the frame 4 to the position shown in Fig. 1, completing the cycle.

After the bag filling has been completed, the holder may be easily and quickly disassembled by releasing the hook 7 of the spring from the pin 8, and the standard 3 withdrawn from the frame 4 and base 1, permitting the parts to be stored in compact form for storage or shipment.

Many modifications of our invention, within the scope of the appended claims, may be made, without departing from the spirit of our invention.

What we claim is:

45 In a bag holder of the kind having two horizontal spreader bars pivoted on vertical axes, with means for normally forcing them to swing from each other at their front ends, in combination with said spreader bars, two horizontal bag engaging members pivoted adjacent to their middle portions on vertical axes to said spreader bars respectively, forward of the axes of the latter, and adapted for insertion into and have their four ends engage and support the bag at four corners and hold the mouth of the bag open.
